(57) **CLAIM**

The ornamental design for a mineral pet chew as shown and described.

DESCRIPTION

FIG. 1 is a front, top and right side perspective view of a first embodiment of a mineral pet chew;

FIG. 2 is a right side elevation view thereof;

FIG. 3 is a left side elevation view thereof;

FIG. 4 is a back elevation view thereof;

FIG. 5 is a front elevation view thereof;

FIG. 6 is a top plan view thereof;

FIG. 7 is a bottom plan view thereof;

FIG. 8 is a front, top and right side perspective view of a second embodiment of a mineral pet chew;

FIG. 9 is a right side elevation view thereof;

FIG. 10 is a left side elevation view thereof;

FIG. 11 is a back elevation view thereof;

FIG. 12 is a front elevation view thereof;

FIG. 13 is a top plan view thereof;

FIG. 14 is a bottom plan view thereof;

FIG. 15 is a front, top and right side perspective view of a third embodiment of a mineral pet chew;

FIG. 16 is a right side elevation view thereof;

FIG. 17 is a left side elevation view thereof;

FIG. 18 is a back elevation view thereof;

FIG. 19 is a front elevation view thereof;

FIG. 20 is a top plan view thereof;

FIG. 21 is a bottom plan view thereof;

FIG. 22 is a front, top and right side perspective view of a fourth embodiment of a mineral pet chew.

FIG. 23 is a right side elevation view thereof;

FIG. 24 is a left side elevation view thereof;

FIG. 25 is a back elevation view thereof;

FIG. 26 is a front elevation view thereof;

FIG. 27 is a top plan view thereof; and,

FIG. 28 is a bottom plan view thereof.

The broken lines shown in FIGS. 2-5, 7, 9-12, 14-22 and 25-28 illustrate portions of the mineral pet chew that form no part of the claimed design. The break lines shown in the middle portions of the mineral pet chew in FIGS. 15-17, 20-22, 25-28 indicate that the appearance of any portion of the article between the break lines forms no part of the claimed design.
